Primary Examiner — Elizabeth Albert

(74) *Attorney, Agent, or Firm* — Leydig, Voit & Mayer, Ltd.

(57) **CLAIM**

The ornamental design for a clipboard, as shown and described.

DESCRIPTION

FIG. 1 is a perspective view taken from the top, front, and right side of a clipboard showing my new design;

FIG. 2 is a top plan view of the clipboard shown in FIG. 1;

FIG. 3 is a bottom view of the clipboard shown in FIG. 1;

FIG. 4 is a front elevational view of the clipboard shown in FIG. 1;

FIG. 5 is a rear elevational view of the clipboard shown in FIG. 1;

FIG. 6 is a left elevational side view of the clipboard shown in FIG. 1;

FIG. 7 is a right elevational side view of the clipboard shown in FIG. 1;

FIG. 8 is a perspective view taken from the top, front, and left side of another embodiment of a clipboard showing my new design;

FIG. 9 is a top plan view of the clipboard shown in FIG. 8;

FIG. 10 is a bottom view of the clipboard shown in FIG. 8;

FIG. 11 is a front elevational view of the clipboard shown in FIG. 8;

FIG. 12 is a rear elevational view of the clipboard shown in FIG. 8;

FIG. 13 is a left elevational side view of the clipboard shown in FIG. 8; and,

FIG. 14 is a right elevational side view of the clipboard shown in FIG. 8.

The broken lines showing features on the clipboard in FIGS. 1, 2, 4-9, and 11-14 are included for the purpose of showing environmental features that form no part of the claimed design.

1 Claim, 10 Drawing Sheets
